[57] CLAIM

The ornamental design for a combined fluorescent lantern, spotlight, and emergency blinking light, as shown and described.

DESCRIPTION

FIG. 1 is a front elevational view of a combined fluorescent lantern, spotlight, and emergency blinking light showing my new design;

FIG. 2 is a right side elevational view thereof;

FIG. 3 is a rear elevational view thereof;

FIG. 4 is a top plan view thereof;

FIG. 5 is an underside plan view thereof;

FIG. 6 is a front elevational view thereof with the head of the lantern extended to show the internal lens, the rear and sides of the internal lens being identical to the front.

FIG. 6.

FIG. 4.

FIG. 5.

FIG. 3.

FIG. 2.

FIG. 1.
